LOW-ANGLE RADIATION ANTENNA

Charles L. Jeffers, San Antonio, Tex.

Application March 2, 1948, Serial No. 12,592

6 Claims. (Cl. 250—33)

1

This invention relates to a radio antenna system especially useful as a broadcasting antenna, although it is not limited to this use.

An object of the invention is to devise an antenna system which radiates very little energy over a rather wide high-angle range and at the same time provides a substantial gain in signal strength over the usual single vertical antenna.

Still another object of the invention is to devise an antenna system in which the angle of minimum radiated energy can be varied electrically from 40 to 60° with respect to the horizontal, thus permitting adjustment of the fading wall for maximum primary service.

The above objects and others are attained by forming the antenna system of two vertically aligned sections which are excited by in-phase currents of predetermined relative magnitudes, and the dimensions of the two antenna sections are chosen to reduce the high-angle radiation and increase the low-angle radiation.

My invention will be described in connection with the accompanying drawing in which

Figure 1 is a diagrammatic representation of the antenna system;

Figures 2 and 3 are radiation curves for the different components of the antenna system;

Figure 4 is a diagrammatic showing of one specific form of antenna system according to my invention;

Figure 5 is a diagrammatic showing of a second form of the antenna system; and

Figure 6 shows three radiation curves for different current ratios in the two sections of the antenna.

The primary service area of a broadcast station is important from a service and a commercial point of view. The ideal antenna for a high powered broadcast station, providing both a groundwave and a skywave service, should have a vertical radiation characteristic such that the skywave signal does not interfere with the desirable groundwave service. The nighttime primary service area would then be practically as large as the daytime area, since the fading or distortion wall would not be the limiting factor. It is further desirable that the skywave signal strength rise rapidly in order to limit the intense fading area to a narrow band around the station.

The power, frequency, and the ground conductivity around the individual station, determine the signal strength at a given location, while the general noise level fixes the minimum signal intensity required to provide a satisfactory service. Thus, the limit of satisfactory service is unique

55 with each individual station; and a definite vertical radiation characteristic is required to achieve the ideal in each case.

In recent years, considerable work has been done towards improving the vertical radiation characteristics of broadcast antennas, and today a tower of uniform cross-section and approximately 0.53 wavelength high is generally used to secure the maximum nonfading range. This antenna is still far from ideal since the distortion zone usually limits the primary service area at night. This undesirable limitation is caused by the radiation of considerable power at the higher vertical angles.

10 15 My improved antenna system radiates practically all energy at angles below 50 degrees of the horizontal and extremely little energy above this elevation. Further, this angle can be varied from 40 to 60 degrees by a simple electrical adjustment with but a small increase in higher angle radiation. These limits are equivalent to distances of 80 to 160 miles for the first reflection skywave signal, fixing the location of the center of the fading zone at approximately 100 to 200 miles from the transmitter.

20 25 My antenna system broadly consists of two vertical elements, one directly above the other as shown in Fig. 1. It is apparent that this is a combination of an antenna 1 at ground elevation and an antenna 2 elevated above the earth. The vertical radiation characteristics of each of these antenna types are well known. It is the unique combination of these two antennas into a single radiator that reduces the high angle radiation.

30 35 In Fig. 1, the section 1 at ground elevation has a length A; and the elevated section 2 has a length B with the center of this section at a height H above ground. The dimensions A, B and H may be expressed in degrees of the wavelength λ in free space as follows:

$$\begin{aligned} A &= 360 (a/\lambda) \text{ degrees} \\ B &= 360 (b/\lambda) \text{ degrees} \\ H &= 360 (h/\lambda) \text{ degrees} \end{aligned}$$

40 45 where a , b and h are the corresponding distances expressed in the same unit of length as λ .

The antenna sections are excited or driven so that the loop currents in elements 1 and 2 are in phase. If the magnitude of the loop current in 1 is considered as unity, the current ratio can be expressed as

$$m = I_2/I_1 = I_2 \quad (1)$$

the vertical radiation characteristic for the lower section 1 is

$$K_{Af}(\theta) = [\cos(A \sin \theta) - \cos A]/\cos \theta \quad (2)$$

where θ is the angle above the horizontal. For the upper section 2, which for simplicity in calculations is considered a half-wave element, the vertical characteristic is

$$K_{Bf}(\theta) = 2m \cos(90 \sin \theta) \cos(H \sin \theta)/\cos \theta \quad (3)$$

and for both sections, adding (2) and (3), we have

$$K_0 f(\theta) = [\cos(A \sin \theta) - \cos A] + 2m \cos(90 \sin \theta) \cos(H \sin \theta) \quad (4)$$

The form factor, K_0 , referred to the current loop is

$$1 - \cos A + 2m$$

and the vertical radiation characteristic for the antenna is

$$f(\theta) = \frac{\cos(A \sin \theta) - \cos A + 2m \cos(90 \sin \theta) \cos(H \sin \theta)}{(1 - \cos A + 2m) \cos \theta} \quad (5)$$

Since the vertical characteristic of a half wave element in space ($\cos(90 \sin \theta)/\cos \theta$), is practically equal to $\cos \theta$, Equation 4 and likewise 5 will hold as an approximation if the upper element is made less than one half wave long.

The form factor, K_0 , is a constant for a particular combination of element length, A , and current ratio, m , and $\cos \theta$ affects both elements similarly; therefore it is convenient to omit the effect of the denominator of Equation 5 in developing the optimum design of an antenna to give a particular radiation characteristic. This is done by evaluating separately the first part of the numerator of (5) for

$$K_0 \cos \theta f(\theta)_A = \cos(A \sin \theta) - \cos A \quad (6)$$

and the second part of the numerator for

$$K_0 \cos \theta f(\theta)_B/m = 2 \cos(90 \sin \theta) \cos(H \sin \theta) \quad (7)$$

Fig. 2 is a plot of Equation 6, $K_0 \cos \theta$ times the vertical radiation characteristics of the lower section 1 for various lengths A , while Fig. 3 is a similar plot of Equation 7 for the upper section 2 for certain center heights H .

In Fig. 2 curves 6, 7 and 8 show the characteristics for three different lengths of lower section 1, that is, for A values of 140° , 120° and 100° , respectively. On Fig. 3 curves 3, 4 and 5 show the characteristics for three different heights of the section 2, that is, for H values of 190° , 210° and 230° , respectively.

An examination of Fig. 3 shows, for the values of H considered, that the field from the elevated element goes through a phase reversal around 25° degrees, and above this point will be 180° degrees out of phase with the high angle field from the lower element. If the parameters A and H are correctly selected and if the loop current in the elevated element is made less than the current in the lower element by the proper amount, the fields of the two elements can be made nearly equal and will cancel for angles deviating considerably from the vertical.

Figure 6 shows the radiation characteristic of the combined radiation from both vertical sections of the antenna system, for three different current ratios. For curve 40, the current ratio m is 0.9, for curve 50 the ratio is 0.69, and for curve 60 the ratio is 0.6. These curves are for dimensions of $A=120^\circ$, $B=180^\circ$ and $H=210^\circ$.

From Figure 6 it will be seen that the angle of zero radiation may be shifted from 40° to 60° degrees simply by changing the current ratio in the two antenna sections, and this involves only an electrical adjustment.

It is of interest to note from Figure 6 that for the design of zero radiation at 50° degrees, the maximum high-angle radiation occurs at 56° degrees where it is less than 0.02 of that in the horizontal plane.

The theoretical field gain of my antenna, for an m ratio of 0.69, is 14.5% compared to a 0.53 wavelength antenna, or 41.5% referred to a quarter wavelength antenna. These field gains are equivalent to power gains of 32 and 100 per cent respectively.

The advantage of my antenna system may be shown by comparing its performance with that of a 0.53 wavelength antenna. Both antennas are assumed to radiate a field of 1770 millivolts per meter at one mile on a frequency of 1000 kilocycles over earth with a conductivity of 10^{-13} E. M. U. The skywave signal values are for 50% of the time. For the 0.53 antenna, the center of the fading zone is at 127 miles where the groundwave signal has an intensity of 0.6 mv./m. My antenna has the same distortion point at 164 miles and at a signal intensity of 0.29 mv./m. The width of the two-to-one signal ratio skywave and groundwave fading zone has been reduced from 36 miles to 24 miles because of the difference in the angle of the skywave signal rise. In other words, the distortion zone of bad fading has been moved from a point of good rural primary service to a point where the groundwave signal strength is hardly adequate for year round noise-free reception. If a current ratio, m , of 0.9 is used, the point of maximum fading would be moved to a distance of 185 miles for a signal level of 0.2 mv./m.

Two physical embodiments of my improved antenna system are diagrammatically illustrated in Figures 4 and 5.

In Figure 4 the lower antenna section 1 is formed of a vertical metallic tube 12 in which is positioned a coaxial cable 13 containing a center conductor 14 and being grounded at its lower end. The upper end of tube 12 is connected to cable 13 at 17, and the tube 12 is also connected to the cable 13 at the point 18 located one-quarter wavelength above the lower end of tube 12 which is insulated from the cable 13 by insulator 9. The upper antenna section is formed of two aligned tubular sections 10 and 11 positioned above the lower section 1. Tubular section 10 is supported on section 11 by an insulator 9a, and the lower end of this section is connected to the center conductor of the coaxial cable 13 at 15. The upper end of middle tubular section 11 is connected to the outer conductor of cable 13 as shown at 16, and the lower end of this section is supported on the cable 13 by the insulator 9b.

The two sections of the antenna are excited with energy from a transmission line 22 through a suitable phasing and power dividing network 21, the lower section 1 being excited through connection 19 to the lower end of tube 12, and the upper section being excited by connection 20 to the lower end of the center conductor 14 of the coaxial cable 13.

In the arrangement shown in Figure 5 the lower section 1 of the antenna is formed of a vertical tubular portion 24 which is insulated from the ground and is excited by a connection 25 from

the phasing network 27 connected to transmission line 28. The upper section 2 of the antenna system is formed of a linear conductor 23, which may be in the form of a conducting tube or a tower, supported on insulator 9d and extending upwardly through the tube 24 and beyond the upper end of this tube to the distance B. The tube 24 is supported on the antenna part 23 by insulators 9 and 9c. Antenna section 2 is excited by a connection 26 to the lower end of part 23 from the phasing network 27.

It will be understood that by suitable adjustment of the phasing networks 21 and 27, the loop currents in the two antenna sections are adjusted to in-phase relation, and the amplitudes of the currents are also adjusted to the desired values as explained above.

It will be further understood that top loading of the top part of the elevated section 2 would still preserve the required electrical length yet reduce the physical length substantially.

I claim:

1. An antenna system comprising a vertical antenna section extending above ground a distance of substantially 120 degrees of the operating wavelength, a second vertical antenna section arranged immediately above said first section and in alignment therewith, said second section having a radiating length of not more than one-half wavelength, and the center of the radiating part of said second section being positioned above ground a distance of substantially 210 degrees of the operating wavelength, and means for exciting said sections by in-phase currents, the loop current in the upper section having an amplitude of substantially 0.7 of the amplitude of the loop current in the lower section.

2. An antenna system comprising a vertical antenna section extending above ground a distance of between 100 to 140 degrees of the operating wavelength, a second vertical antenna section arranged immediately above said first section and in alignment therewith, said second section having a length of not more than one-half wavelength, and the center of said section being positioned above ground a distance of between 190 to 230 degrees of the operating wavelength, and means for exciting said sections by in-phase currents.

3. An antenna system according to claim 2 wherein the ratio of the loop current in the upper section to the loop current in the lower section is within the range of 0.5 to 0.9.

4. An antenna system comprising three vertically aligned tubular sections supported in insulated relation, the lower section having a length of substantially 120° of the operating wavelength, and the two upper sections having lengths of substantially one-quarter wavelength, a coax-

ial cable arranged within said tubular sections and having its lower end grounded, a connection from the center conductor of said cable to the lower end of the upper section, connections from the outer conductor of said cable to the upper ends of the middle and lower tubular sections, a connection between the outer conductor of said cable and the lower tubular section at a point one-quarter wavelength above ground, and exciting connections to the lower end of said lower section and to the lower end of the center conductor of said cable.

5. An antenna system comprising a vertical conductor supported in insulated relation with respect to ground and having a length of substantially 300° of the operating wavelength, a tubular conductor surrounding the lower section of said first conductor for a distance of substantially 120° of the operating wavelength and being insulated therefrom, and exciting connections to the lower ends of said conductors for exciting in-phase currents in the tubular conductor and in the upper section of the first conductor.

25 6. A two-part vertical antenna comprising a lower radiating section insulated from ground and extending from ground to a point above ground a distance of substantially 120 degrees of the operating wavelength, an upper radiating section arranged immediately above said lower section and in alignment therewith, said upper section extending above said lower section a distance of not more than one-half wavelength, and the center of the radiating part of said upper section being positioned above ground a distance of substantially 210 degrees of the operating wavelength, and feed connections to the lower ends of said radiating sections for exciting in-phase currents therein, the loop current in the upper section having an amplitude of substantially 0.7 of the amplitude of the loop current in the lower section.
